SIGHTING DEVICE FOR ORDNANCE.

1,384,007.

Specification of Letters Patent.

Patented July 5, 1921.

Application filed September 3, 1920. Serial No. 408,099.

To all whom it may concern:

Be it known that I, MAX BARTHOLDY, residing at Essen, Germany, a citizen of the German Republic, have invented a certain 5 new and useful Improvement in Sighting Devices for Ordnance, of which the following is a specification, for which I have filed an application in Germany Jan. 23, 1919.

This invention relates to sighting devices 10 for ordnance with a numbered graduation corresponding to the range of the target and is characterized by the fact that of the two members which carry the graduation and the reading off mark belonging thereto the 15 reading off member, which is adjustable for range, is positively connected to the carrier for the means of sighting by a kinematic quadrilateral system the dimensions of which are so chosen that the changes in the 20 position of the reading off member which corresponds to the unequal changes in the angular position of the sighting means carrier corresponding to equal changes of range are sufficiently equalized. Sighting devices 25 of this kind possess the advantage that the pivoted quadrilateral, which permits of the arrangement of the carrier of the means of sighting in any desired position in the well known way, is simultaneously utilized to receive a range graduation with sufficiently 30 uniform distances between the division marks.

The invention will be further described with reference to the accompanying drawings, which show a construction of the invention and in which—

Figure 1 is a side elevation of the sighting device and of the adjacent parts of the gun and

Fig. 2 is a portion of a section on the line 2—2 of Fig. 1.

A denotes the gun barrel, which, when the gun is fired recoils in a cradle B. This latter is mounted by means of the two trunnions b¹ in the gun carriage C. The sighting device of the gun is mounted on the cradle, and has a sighting telescope D, which is mounted on a bar-shaped carrier D¹ for the sighting means. The carrier D¹ is pivotally mounted by means of a pin b² parallel with the axis b¹ of the trunnions on a bracket arm b³ fixed to the cradle and terminates at its rear end in a sector-shaped guide d² arranged coaxially with the pin b². In this sector-shaped guide b² is mounted a

correspondingly shaped sliding piece E, relatively to which the carrier D¹ for the sighting means can be adjusted by means of a spiral pinion F mounted on the guide d² and engaging in a series of teeth e¹ on the 60 sliding piece for the purpose correcting its angular position. By this adjustment correction may be made to accommodate such conditions as density of the atmosphere, elevation of the position of the gun with respect to the target, etc.

The extent of this correction can be read off by means of a mark d³ on the guide d² relatively to a graduation arranged on the sliding piece E and having its zero mark in 70 the middle. To the sliding piece E is attached one end of a connecting rod G, which at its other end is connected to a crank arm H. This latter is rigidly connected to a worm wheel H¹, which is rotatably mounted 75 in a casing b⁴ fixed on the rear end of the cradle B. In the casing b⁴ is mounted a worm J rigidly connected to a shaft provided with a milled head i¹ and gearing with the worm wheel H¹. The worm gear J H¹ 80 serves to impart to the carrier D¹ for the sighting means the angular position relatively to the gun barrel, which corresponds to the range of the target. The range of the target is read off on a range graduation 85 h³, which is arranged on an annular sector-shaped rib h² on the worm wheel H¹, and a reading off mark b⁶, which is placed on the edge of an aperture b⁵ through which the graduation h³ is visible. When the quadrilateral system, which is formed by the cradle B, the crank arm H with the worm wheel H¹, the connecting rod G and the sliding piece E with the carrier D¹ for the sighting means adjusted at the zero point of 90 the graduation e², is so adjusted by the worm gear H¹ J that the sighting line of the telescope D is parallel with the longitudinal axis of the gun barrel, and the mark b⁶ consequently points to the zero point of the 95 graduation h³, the crank arm H of the quadrilateral system situated next to the adjustable reading off member H¹ h² is directed obliquely downward and forwardly and forms with the connecting rod G, which 100 constitutes the coupling member of the system an acute angle, while the other crank arm of the system formed by the carrier D¹ and the sliding piece E describes an obtuse 105 angle with the connecting rod G.

By suitably selecting the dimensions of these parts it is easy to insure that the unequal changes in the angular position of the carrier D^1 for the sighting means (corresponding to equal changes in the range of the target) correspond to sufficiently equal changes in the angle of rotation of the crank arm H and of the worm wheel H^1 , that is to say, to sufficiently equal changes in the relative positions of the two members (H^1 h^2 and b^4 b^5) which carry the range graduation and the corresponding reading off mark (b^6), so that the distance between the division marks of the range graduation h^3 is sufficiently uniform.

The kinematic quadrilateral system, which allows of the arrangement of the sighting telescope D in any desired point such for example in the vicinity of the lookout slit 20 in an armored shield (not shown) mounted on the gun carriage, is also used at the same time to obtain a range graduation with a sufficiently uniform distance between the division marks.

25 **Claims:**

1. A device of the class described comprising a sighting means, a carrier for said sighting means, a device for indicating the range, which embodies a casing and a rotatable member, with means for rotating said member, one end of the sighting means carrier terminating in a sector-shaped guide, a slidable member mounted in said guide, means for varying the position of the slidable member in said guide, arms operatively connecting said slidable member and rotatable member, said parts being arranged to form a kinematic quadrilateral system, substantially as and for the purpose set forth.

40 2. A sighting device of the class described comprising a sighting telescope, a sighting means carrier, a sector-shaped guide formed at one end of said carrier, a sliding member mounted in said guide, means for adjusting the position of said sliding piece with respect to said guide, a range indicating device embodying a casing, a worm-wheel and means for rotating said wheel, an arm rigidly connected to said worm-wheel, a second arm operatively connecting the sliding member to the first-mentioned arm, said parts forming a kinematic quadrilateral system, said second arm forming with said first arm an acute angle and with the sighting means carrier an obtuse angle, substantially as described.

45 5. A sighting device for ordnance comprising a gun barrel and supporting parts, a sighting means carrier rotatable relatively to a gun part adapted to turn in unison with

the gun-barrel, an adjustable member rotatably mounted on said gun part, means for adjusting said member for range, a range indicating device having a reading off member carrying a range scale, and a rod 65 pivotally connecting said adjustable member and said sighting means carrier, said adjustable member, the sighting means carrier and the connecting rod forming a kinematic system of an automatically variable 70 ratio of transmission for equalizing the distance between the division marks of said range scale.

4. A sighting device for ordnance comprising a gun barrel and supporting parts, 75 a sighting means carrier rotatable relatively to a gun part adapted to turn in unison with the gun-barrel, an adjustable member rotatably mounted on said gun part, means for adjusting said member for range, a range indicating device having a reading off member carrying a range scale, and a rod pivotally connecting said adjustable member and said sighting means carrier, said adjustable member and the sighting 80 means carrier forming the crank arms of a kinematic quadrilateral system in which when said adjustable member is adjusted for the range of zero one crank arm is arranged at an acute angle with said connecting rod and the other crank arm is arranged at an obtuse angle with said rod.

5. A sighting device for ordnance comprising a gun barrel and supporting parts, 95 a sighting means carrier rotatable relatively to a gun part adapted to turn in unison with the gun barrel, an adjustable member rotatably mounted on said gun part, means for adjusting said member for range, a range indicating device having a reading 100 off member carrying a range scale, a sliding piece mounted on said sighting means carrier, means for adjusting said sliding piece relatively to said sighting means carrier for range corrections, and a rod pivotally connecting said adjustable member and said sliding piece, said adjustable member, the sighting means carrier with the sliding piece mounted thereon and the connecting rod forming a kinematic system of an automatically 105 variable ratio of transmission for equalizing the distance between the division marks of said range scale.

The foregoing specification signed at Essen, Germany, this 15th day of June, 1920. 110

MAX BARTHOLDY.
